SNATCH BLOCK

Albert G. Frankhouser, Lima, Ohio, assignor to
The H. G. Shock Company, Lima, Ohio, a corporation of Ohio

Application April 3, 1944, Serial No. 529,328

9 Claims. (Cl. 254—193)

1

This invention relates to a snatch block, and more particularly deals with a block of the opening type which may be opened under full load to gain access to the sheaves or pulleys.

The nature of the present invention will be fully understood from the following description taken in connection with the annexed drawings, wherein:

Fig. 1 is a side elevational view, partly in cross-section, of the snatch block of the present invention.

Fig. 2 is an end elevational view, partly in cross-section and with some elements removed, illustrating a three-sheave block.

Fig. 3 is an end elevational view, partly in cross-section, similar to Fig. 2 but illustrating a four-sheave block; and,

Fig. 4 is an end elevational view, partly in cross-section, similar to Figs. 2 and 3 but illustrating a five-sheave block.

Referring to Fig. 1, 10 is a top ring mounted on a hanger 11, and 12 is the bottom ring mounted on a hanger 13. The hanger 11 is carried by a bolt 12a which also supports a fork, clevis or bracket 13a and a second fork, clevis or bracket 14 (see Fig. 2). The fork 13a and the fork 14 are provided with a hole 15 adapted to receive a cotter pin 16, and they are also provided with another hole 17 adapted to receive a pin 18. The prongs of the forks 13a and 14 are drilled to receive a sectional insert 19. The lower portion of the hanger 11 is drilled in juxtaposition with the drilling of the prongs of the forks 13a and 14, and each section of the insert 19 (which consists of 2 parts) passes through the several prongs of one fork and into the opening on the lower portion of the hanger 11. As illustrated in Fig. 2, the insert 19 passes through the prongs of the fork 13a and half way into the opening at the lower portion of the hanger 11 and is locked in place by the pin 18 and by the cotter pin 16. When the cotter pin 16 is removed, the pin 18 may be used as a handle for withdrawing the insert 19. The other half or section of the insert 19 is shown withdrawn as the invention is illustrated in Fig. 2.

Referring further to Fig. 1 and Fig. 2, 20 and 21 are the side plates of the block and are hung on the insert 19 and thus supported by the forks 13a and 14 respectively. The side plates 20 and 21 are held together at the bottom portion thereof by a cross-bar 22a which also supports the hanger 13. Said plates 20 and 21, with cross-bar 22a, constitute a frame or shell. A plurality

2

of sheaves 22 are supported between the side plates 20 and 21 by a bolt 23 provided with a bushing 24. The sheaves are separated by spacer bars 25.

In Fig. 3, 26 is a top ring supporting a hanger 27 through which passes a bolt 28. The bolt 28 also passes through a fork 29 and a fork 30. The prongs of the fork 29, the prongs of the hanger 27 and the prongs of the fork 30 are drilled in juxtaposition to receive an insert 31 in two sections one of which sections is shown in place in Fig. 3 and the other section of which is not shown. The outer prong of the fork 29 and the outer prong of the fork 30 are provided with an opening 32 adapted to receive a cotter pin 33, and the end of each section of the insert 31 is provided with a pin 34 insertable in an opening 35 and adapted to serve as a handle when the insert 31 is to be withdrawn.

20 The forks 29 and 30 support side plates 36 and 37 which are joined together at their lower portion by a bar 38 supporting a hanger 39 provided with a bottom ring 40. On the side plates 36 and 37 is mounted a bearing bolt 41 provided with a bushing 42 and supporting a plurality of sheaves or pulleys 43. A plurality of dividing plates 44, 45 and 46 are provided, each of which is supported by the insert 31.

In Fig. 4, 47 is a top ring mounted on a hanger 48 which is drilled to receive a bolt 49. On the bolt 49 are mounted a fork 50 and a fork 51. The prongs of the fork 50 and of the fork 51 and the bottom portion of the hanger 48 are drilled in juxtaposition to receive an insert 52 consisting of two parts, one of which parts is shown in position in Fig. 4 and the other part of which is shown removed in Fig. 4. The outer prong of the fork 50 and the outer prong of the fork 51 are provided with an opening 53 adapted to receive a cotter pin 54, and the outer ends of each section of the insert 52 is provided with a pin 55 insertable in an opening 56 which serves as a handle to withdraw the insert 52 when the cotter pin 54 has been removed and the insert 52 is to be removed.

45 Side plates 56a and 57 are hung on the insert 52 and are joined at the lower portions thereof by a bar 58 which also supports a hanger 59 provided with a bottom ring 60. A plurality of sheaves 61 are mounted between the side plates 56a and 57 on a bearing bolt 6 provided with a bushing 63, and a plurality of dividing plates 64, 65, 66 and 67 are mounted on the insert 52.

Referring to Fig. 2, if it should be desired to replace a rope or cable running over either of the outer sheaves, it is only necessary to remove the

cotter pin 16, withdraw one half of the insert 19 using the pin 18 as a handle, moving to one side the fork 13a using the bolt 12a as a pivot, and dropping the rope or cable over the sheave between the side plate and the dividing plate. The fork 13a would then be dropped into position, the insert 19 would be replaced, and the cotter pin 16 would be replaced and locked in position. This would place the block in proper condition for operation.

Still referring to Fig. 2, if it were desired to place a rope or cable over the center sheave of the block it would only be necessary to remove the cotter pin 16, withdraw the insert 19 by pulling on the pin 18, pushing to one side the fork 13a, and causing the dividing plate thus released to fall freely. The rope or cable could then be placed over the center sheave and the assembly brought to its original condition. It will be noted that in either event, the load on the block would not have to be removed. The full load would be carried by one side plate and one dividing plate hung on one of the forks and on the hanger 11 by one half of the insert 19.

Referring now to Fig. 3, it will be noted that the same procedure could be followed to place a rope over any of the sheaves, and that in every instance the full load would be carried by one half of the insert 31, the dividing plate 45, the hanger 27 and either the side plate 36 and the dividing plate 44 or the side plate 37 and the dividing plate 46. In no event would it be necessary to relieve the block of its load to replace a rope or cable.

Referring now to Fig. 4, it will be noted that the same condition would exist here. Irrespective of the sheave over which the rope or cable is to be placed, the full load would be supported by one half the insert 52, the hanger 48 and either the side plate 56a and the dividing plates 64 and 65 or the side plate 57 and the dividing plates 66 and 67, depending on which side or half of the insert 52 is removed.

Those skilled in the art will readily understand that the snatch block of the present invention offers many advantages over snatch blocks previously known or used. It will be noted principally that in no event is it necessary to relieve the load on the block in order to replace a rope or cable over any of the sheaves.

It will be further understood that while there have been described herein and illustrated in the annexed drawing certain embodiments of this invention, it is not intended thereby to have this invention limited to or circumscribed by the specific details of construction, arrangement of parts, proportions or dimensions described or illustrated, in view of the fact that the present invention is susceptible to changes or modifications without departing from the spirit of this disclosure and the scope of the appended claims.

I claim:

1. In a pulley block, a frame including opposed side plates, a plurality of pulleys pivoted on aligned axes in said frame, a hanger, a pair of clevises, means pivoting said clevises on opposite sides of said hanger, each clevis being adapted to embrace a portion of a respective plate, there being aligned holes in said hanger, frame and clevises, and a two-part pin, each part passing through a respective clevis, plate, and into the hole in said hanger, whereby said block may be reeved by successive removal of said pin parts and pivoting of said clevises free of said frame.

2. A sheave block comprising a shell including side plates, a plurality of sheaves coaxially

pivoted between said plates, a hanger, spacer plates between adjacent sheaves, a depending bracket pivoted on each side of said hanger, there being aligned holes in said hanger, brackets and all said plates, and first and second pin means passing through said holes and axially shiftable therein, each of said pin means passing through only one of said brackets and at least into the hole in said hanger.

10. 3. In a sheave block, a forked hanger, a pair of clevises coaxially pivoted on respective opposite sides of said hanger, a frame having end plates each having a portion embraced by the respective clevises, a spacer plate between the forks of said hanger, a plurality of pulleys, pivot means for said pulleys passing through all said plates, each pulley being between a respective end plate and said center plate, there being aligned holes in said hanger, plates and clevises, a pivot pin passing through said holes in one clevis, one end plate, one fork of said hanger, and into said spacer plate, and a second pin passing through said holes in the other clevis, end plate, fork of said hanger and into said spacer plate.

25. 4. A snatch block comprising a frame, a plurality of sheaves pivoted in said frame, a hanger, brackets coaxially pivoted on said hanger and depending therefrom, and separate pins passing through aligned holes in said frame, hanger and brackets, each of said pins extending completely through one only of said brackets and into said hanger.

30. 5. In a sheave block, a U-shaped frame having a plurality of sheaves pivoted therein, a hanger, brackets pivoted on opposite sides of said hanger and depending therefrom, there being normally aligned holes in said hanger, brackets, and legs of said frame, and a two-part pin passing through said holes, the adjacent ends of said

40. parts lying within the hole in said hanger.

6. In a three-fold sheave block, a U-shaped frame having end plates, two spacer plates, sheaves pivoted in said frame on a common axis, each sheave lying between a pair of plates, a hanger, clevises pivoted on opposite sides of said hanger and depending therefrom to embrace a portion of a corresponding frame plate, each spacer plate having a portion embraced between a corresponding side of said hanger and a clevis, and a two-part pin passing through aligned holes in said hanger, plates, and clevises, the adjacent ends of said parts lying within the hole in said hanger, whereby said block may be reeved by bighting.

55. 7. In a pulley block, a frame having side plates, pulley means journalled in said frame, a bracket associated with each of said side plates, a connecting member passing through each of said brackets and the associated said side plate, a hanger, and means pivotally connecting said hanger and said brackets, said hanger having a portion adapted for receiving at least the ends of said connecting members.

60. 8. In a pulley block, a pair of side plates, a plurality of pulleys, means journalling said pulleys between said plates, a hanger, a clevis pivoted on each side of said hanger, first aligned holes in one of said clevises, the adjacent side plate and said hanger, second aligned holes in the other of said clevises, the other of said side plates and said hanger, first and second pins extending through said first and second aligned holes respectively, and means detachably securing said pins in their respective holes.

9. In a sheave block, a plurality of sheaves coaxially pivoted, a plurality of plates separating said sheaves and pivoted coaxially therewith, a first bracket associated with a portion of said plates and a second bracket associated with a remainder of said plates, first and second connecting means extending through said first and second brackets, respectively, and their associated plates, a hanger pivotally secured to said brackets, and means associated with said hanger for receiving at least the ends of both of said connecting means.
